(57) **CLAIM**

The ornamental design for a camera enclosure, as shown and described.

DESCRIPTION

FIG. 1 is a front perspective view of a camera enclosure showing our new design with the enclosure flap closed; FIG. 2 is a front perspective view thereof, with the enclosure flap open;

FIG. 3 is a top plan view thereof, with the enclosure flap open as shown in FIG. 2;

FIG. 4 is a side elevational view thereof, with the enclosure flap open as shown in FIG. 2;

FIG. 5 is a front end elevational view thereof, with the enclosure flap open as shown in FIG. 2; and,

FIG. 6 is a rear end elevational view thereof, with the enclosure flap closed as shown in FIG. 1.

The broken lines in the Figures are for illustrative purposes only and form no part of the claimed design.
